UNITED STATES PATENT OFFICE.

LOUIS N. D. WILLIAMS, OF OGONTZ, PENNSYLVANIA.

STITCH-TRANSFERRING DEVICE FOR KNITTING-MACHINES.

1,174,647.

Specification of Letters Patent.

Patented Mar. 7, 1916.

Application filed April 30, 1915. Serial No. 24,909.

To all whom it may concern:

Be it known that I, LOUIS N. D. WILLIAMS, a citizen of the United States, residing in Ogontz, Pennsylvania, have invented 5 certain improvements in Stitch-Transferring Devices for Knitting-Machines, of which the following is a specification.

The object of my invention is to provide 10 simple and efficient means for first removing stitches from needles on one side of a knitting machine (particularly those on one side of the diameter of a needle cylinder) and then removing stitches from needles on the opposite side thereof, the stitches so removed being thus doubled, so that they can 15 subsequently be readily united. This object I attain in the manner hereinafter set forth, reference being had to the accompanying drawings, in which—

20 Figure 1 is a vertical sectional view of sufficient of the needle cylinder of a circular knitting machine to illustrate the application of one form of my invention thereto; Fig. 2 is a view similar to Fig. 1 but showing another adaptation of my invention, and 25 Fig. 3 is a bottom view of the web holder operating cam ring.

In the drawings, 1 represents the cylinder 30 of a circular knitting machine, 2 the needles around one-half of the cylinder, 2^a the needles around the other half of the same, 3, 3^a the web holders, 4 the ring in which said web holders are slidably mounted, and 35 5 the cam ring for imparting to-and-fro reciprocation to said web holders, all of these parts being constructed and operating in the usual manner. The cam ring 5 should, however, be provided with means, such for instance as the switch cam 5^a, Fig. 3, for retaining all of the web holders in retracted 40 position when desired.

Mounted inside of the upper portion of the cylinder shown in Fig. 1 is a ring comprising two semi-circular halves 6—6^a having hinge members 7—7^a with pintle 8, in line with the tops of a series of upwardly projecting stitch receiving points 9 on the ring member 6, the tops of these points normally occupying a position below the stitch retaining portion of the web holders. A 50 supporting cylinder 10, however, provides for lifting the ring segments 6—6^a when desired.

Supposing that the knitting operation has 55 been completed upon the needles 2—2^a and it is desired to double upon the semi-circular

set of points 9 stitches from the needles 2 and those from the needles 2^a, the ring segments 6—6^a are lifted until the points 9 have received upon their upper ends the stitches 60 last formed upon the needles 2 or the stitches of a previously formed course. The needles 2, before or after this operation, having been projected to such a position that the latches are clear of the stitches, said needles 2 are 65 then retracted so as to cast the stitches therefrom and the web holders 3 having previously been retracted, the section 6 of the ring and its points 9 is then swung to the reverse position shown by dotted lines 70 in Fig. 1, so that each of the points registers with a corresponding needle 2^a on the opposite half of the knitting machine. After the points have engaged the stitches carried by the needles 2^a, or the stitches of a previous course, the needles 2^a are actuated so 75 as to cast their stitches, the web holders 3^a are retracted, and the points 9, each with two stitches upon it, can then be removed from the machine along with the ring segments 6, 6^a and the two courses of stitches 80 can then be united by looping them together in an ordinary looping machine.

Instead of using ring segments on the inside of the needle cylinder they may be disposed upon the outside of the needles, as 85 shown in Fig. 2, and in such case, when the web holders have been retracted, the points 9 engaged with the stitches upon the needles 2 and said stitches cast or otherwise freed 90 from said needles the points with the stitches upon them may be moved to the position shown by dotted lines, and may either receive the stitches from the needles 2^a or the points may transfer the stitches carried by 95 them onto said needles 2^a to be knitted into a succeeding web.

In Figs. 1 and 2 of the drawings I have only shown a single needle at each side of the needle cylinder and a single point 9 on the ring segment 6 as the showing of all of the needles and points would lead to confusion and is not necessary for a proper understanding of my invention.

While it is always preferable to hinge the 105 semi-circular quill carrier to a fixed member, such fixed hinges are not absolutely necessary to the proper carrying out of my invention, as the stitches of the web at and near the terminal points of the set may 110 serve as hinges when swinging the points from the position shown by full lines to

that shown by dotted lines, and although my invention has been designed particularly with reference to doubling stitches produced upon the needles of one-half of a circular 5 knitting machine with those produced upon the needles at the opposite half of the machine it can, with advantage, be used in connection with that type of knitting machine in which two straight parallel rows of 10 needles are employed arranged back to back and with just sufficient space between them for the passage of the knitted web.

I am aware of the patent of Walter D. Butz, numbered 1,068,853 and dated July 15 1913, in which two semi-circular series 20 of stitch receiving points were hinged together in line with the ends of the points, the circular series of quills first receiving the stitches from the needles of a circular knitting machine and one-half of the points being then turned over so as to be directed toward the other half of the points so that the stitches from one set of points could be transferred to the other set and doubled 25 thereon with the stitches already upon them, but in carrying out my invention I only use one set of points which co-act directly first with one set of needles and then with the opposite set the doubling operation being 30 effected simultaneously with transfer of the second set of stitches.

I claim:

1. As a means of doubling stitches formed at one side of a knitting machine with 35 stitches formed at the opposite side of the same, a series of stitch receiving points mounted so as to register with and receive stitches at one side of the machine, said points being susceptible of assuming a reverse 40 position so as to register with stitches at the opposite side of the machine, and at one and the same operation effect both transfer and doubling of stitches when in the latter position.

2. As a means of doubling stitches formed 45 at one side of a circular knitting machine with stitches formed at the opposite side of said machine, a segmentally disposed series 50 of stitch receiving points mounted so as to register with and receive a semi-circular set of stitches at one side of the machine, said points being susceptible of assuming a reverse position so as to register with a semi-

circular set of stitches at the opposite side of the machine, and at one and the same 55 operation effect both transfer and doubling of stitches when in the latter position.

3. As a means of doubling stitches formed at one side of a knitting machine with 60 stitches formed at the opposite side of the same, a series of stitch receiving points, a carrier therefor, and a fixed member to which said carrier is hinged at a point in line with the tops of the points, whereby 65 said points may be caused to register with and receive stitches at one side of the machine or can be reversed in position and caused to register with stitches at the opposite side of the machine, and at one and the same operation effect both transfer and 70 doubling of stitches when in the latter position.

4. As a means of doubling stitches formed at one side of a knitting machine with 75 stitches formed at the opposite side of the same, a series of stitch receiving points mounted so as to register with stitches at one side of the machine and susceptible of assuming a reverse position so as to register with stitches at the opposite side of the machine, and at one and the same operation 80 effect both transfer and doubling of stitches when in the latter position, and means for moving said points to cause them to engage with the initial stitches before reversal of 85 position.

5. The combination of the needles of a knitting machine, the web holders, means for retaining the latter in the retracted position, and a series of stitch receiving points 90 mounted so as to register with and receive stitches at one side of the machine and susceptible of assuming a reverse position so as to register with stitches at the opposite side of the machine, and at one and the same operation 95 effect both transfer and doubling of stitches when in the latter position.

In testimony whereof, I have signed my name to this specification, in the presence of 100 two subscribing witnesses.

LOUIS N. D. WILLIAMS.
